HIGH TEMPERATURE JET PROPULSION APPARATUS

Herbert E. Grenoble, Amsterdam, N.Y., assignor to General Electric Company, a corporation of New York

Filed Dec. 23, 1957, Ser. No. 704,536

3 Claims. (Cl. 60—35.3)

This invention relates to high temperature gas turbines and related jet apparatus, and more particularly, to a method of operating jet propulsion devices at extreme high temperatures where normal turbine blade and other structural materials have little mechanical strength.

It is well known that many metals and alloys commonly used for structural purposes suffer a substantial loss in their mechanical properties when their temperature is elevated. Some metals, however, exhibit much greater resistance to physical changes at high temperatures and are referred to as refractory metals, such as molybdenum, tantalum, tungsten, and niobium. While these metals retain considerable strength at high temperatures due to their high melting point, they have a common disadvantage of being highly susceptible to oxidation at high temperatures. For example, one of the limitations in operating gas turbine engines at extreme temperatures has been the lack of satisfactory structural materials, particularly those metals from which the turbine bucket or blade is manufactured. The temperature of present gas turbines is generally limited to approximately 1700° F. for present blade metals of the nickel-chromium type. Turbine blades manufactured from the refractory metals as above mentioned may operate in the temperature range exceeding 2000° F. provided their oxidation tendencies can be controlled. Molybdenum, when exposed to high temperatures in air or combusted atmosphere containing some free oxygen, reacts to form a trioxide which becomes a liquid at about 1460° F. and boils at about 2335° F. Tungsten is similarly limited by the existence of a volatile trioxide, although the vapor pressure of the oxide is lower for the same temperature conditions relative to molybdenum. Niobium and tantalum form oxides which are relatively non-volatile and protective, but are embrittled by oxygen or nitrogen taken into solution in the metal phase.

Broadly speaking, of the refractory metals mentioned, molybdenum is least disadvantageous because of its low density relative to tungsten, and because of its limited solubility for oxygen and nitrogen, relative to niobium and tantalum. While the disadvantage of oxidation is common to all of the metals mentioned, it is perhaps most pertinent to the use of molybdenum which is otherwise highly desirable for its high temperature strength and related characteristics. A preferred form of this invention includes the use of molybdenum and its alloys, and a description of the problems associated therewith substantially suffices for the remaining metals of the refractory group.

Since the trioxide of molybdenum becomes a liquid at about 1460° F. there is little protection afforded by this trioxide against continuing oxidation at temperatures in excess of 1460° F. Actually, the oxidation of molybdenum in air may be considered to be rapid at a temperature as low as 1100° F. Therefore, in order to use molybdenum and/or its alloys where the high temperature, high strength characteristics are desired, it has been the practice to form a protective coating or covering on the turbine bucket or blade or other structural members exposed to high temperatures. In this respect it is understood that the life of such a coated or covered blade is particularly limited by the life of the covering itself, and the coating must also be capable of withstanding the high temperatures involved. A solution to the problem

2

may then be found in two conceptions; one, to develop a satisfactory coating or covering which will withstand the high temperatures, or two, to provide combustion gases which are non-oxidizing with respect to the metal employed. This invention is, accordingly, directed to the latter of the above-mentioned solutions.

It is therefore an object of this invention to provide an increased operating temperature for gas turbines or other jet propulsion apparatus.

It is another object of this invention to operate a high temperature gas turbine with turbine blades of a refractory metal including tantalum, niobium, tungsten, molybdenum, and alloys thereof.

It is a further object of this invention to remove the necessity of coverings or coatings for turbine blades and other parts manufactured of a refractory metal and operating under high temperatures where such metals are highly susceptible to oxidation.

It is another object of this invention to provide a non-oxidizing atmosphere adjacent turbine blades or other parts of a refractory metal employed in gas turbines and the like apparatus.

Briefly stated, in accordance with one aspect of this invention, a non-covered or non-coated turbine bucket or other structural part of a refractory metal is employed for continuous operation in a high temperature jet propulsion cycle wherein the gas stream passing adjacent the buckets or other related structure precludes the formation of trioxides on the bucket surfaces through a predetermined greater-than-stoichiometric burning of the fuel, for example, in the combustion chamber of a gas turbine engine. The invention is equally applicable to other jet devices where certain structures exposed to a high temperature gas stream are highly susceptible to extreme oxidation.

While this specification concludes with claims particularly pointing out and distinctly setting forth the invention, the invention will be better understood when taken in connection with the following specification and the drawings thereof, wherein:

FIG. 1 discloses an exemplary application of this invention;

FIG. 2 is a cycle illustration of this invention; and

FIG. 3 discloses a modification of the invention of FIG. 1.

FIG. 1 illustrates one preferred form of this invention as exemplary of an application of this invention applied to a conventional turbojet engine 1. Engine 1 includes a casing 2 provided with an inlet 3 and an exhaust 4. Within the casing 2 there is positioned a compressor 5 connected to a turbine wheel 6. Turbine wheel 6 has mounted thereon suitable molybdenum or molybdenum alloy buckets or blades 7 which are capable of withstanding temperatures in excess of 1700° F. in a reducing atmosphere.

Fuel for the jet engine is injected into combustion chamber 8 through fuel nozzle 9 and the products of combustion within the combustion chamber 8 pass through the turbine buckets 7 for rotation of the turbine wheel 6 and the compressor 5. As heretofore stated, molybdenum and molybdenum alloy buckets are capable of withstanding temperatures in excess of 1700° F. when operated in a controlled atmosphere, and accordingly the fuel-air ratio within the combustion chamber 8 is so regulated as to burn with an excess of fuel, and thus be a gas stream which will not react with the molybdenum blade to form the volatile trioxide of molybdenum. The fuel-rich mixture may produce a satisfactory atmosphere if only rich enough to the extent of forming the dioxide of molybdenum on the turbine buckets, the dioxide being a form of protective coating. Burning a fuel-rich mixture in a gas turbine is an uneconomical process since much of the unburned fuel is exhausted through the engine without

benefit of the available energy therein. Wastefulness of the process may be substantially minimized by introducing additional air into the exhaust duct 4 aft the turbine wheel 6 for further burning. Such a process is quite similar to that known as "re-heat operation," where, in a turbojet engine, additional fuel is injected into the exhaust duct for further burning with a resultant increase in thrust. One means of providing additional air in the exhaust duct of a turbojet engine is illustrated in FIG. 1 by a by-pass passage or tube 10 which permits partial extraction or flow of air from the compressor 5 to be introduced into the exhaust section aft the turbine wheel 6. It is therefore seen that the excess of fuel employed in the primary combustion process as a means of atmosphere and temperature control is further utilized to augment the thrust from the jet by the afterburning or re-heat principle.

The cycle for this process is illustrated in FIG. 2 by an idealized and schematic pressure volume diagram. In FIG. 2, the line AB represents the adiabatic compression of the incoming air to the compressor, while the line BC represents the combustion of the fuel-rich mixture at a constant pressure. Line CD indicates the adiabatic expansion of the burning mixture through the turbine wheel and line DE represents the further combustion in the exhaust duct after the addition of air from the compressor. The cycle concludes with line EF illustrating the adiabatic expansion through the jet outlet. The net work per pound of gas mixture passing through the turbine is given by the enclosed area of the curve ABCDEF in FIG. 2. In comparison, it may be seen that a greater thrust per pound of mass flow is possible from the proposed cycle than is possible from either of two cycles, first, a low temperature cycle without re-heating, or second, by a low temperature cycle with re-heating by the addition of fuel in the exhaust cone. In the former cycle, the net work per pound of gas mixture is indicated by the area enclosed by the included curve ABC' and F', while in the latter cycle the net work per pound of gas mixture is indicated by the shading enclosed by curves ABC'D'E and F.

The proper fuel-air mixture to be employed in this invention in order to obtain satisfactory results must be controlled between limits. The mixture must generally be more than slightly over-rich, and sufficient to limit the gas temperature to approximately 3000° F., the maximum temperature at which a molybdenum or molybdenum alloy bucket may be expected to operate effectively. The extent of the richness of this mixture is also limited by the problem of satisfactory combustion of a highly rich mixture in a rapidly moving gas stream. For example, a molybdenum turbine bucket may be effectively employed in a gas turbine where the temperature of the gas is maintained about 3000° F. by the addition of fuel exceeding the stoichiometric proportion of fuel and air to the extent of about 1½ times the stoichiometric proportion. Under these conditions, the molybdenum operates satisfactorily with little tendency toward rapid deterioration from oxidation.

Various types of control apparatus may be employed in connection with this invention to maintain a constant rich mixture or a selectively variable one. For example, in FIG. 1 control 11 senses the temperature at turbine blades 7 through a suitable temperature responsive device 12. The amount of fuel entering the combustion chamber 8 from the nozzle 9 is thereby controlled to maintain an equilibrium temperature condition at the turbine blades 7. The control 11 may be further correlated with a valve 13 in the by-pass duct 10 of the engine 1 to vary the amount of air to be added to the exhaust duct in a manner proportional to the overly-rich mixture utilized to maintain temperature equilibrium conditions. It is to be understood that such exemplary controls may be suitably integrated to provide the proper temperature or reducing atmosphere at various throttle settings. The particular devices, and/or elements of the control system are quite well known to those skilled in the art, and therefore do not form any part of this invention.

Where the re-heat principle of this invention is not applicable in certain gas turbine installations, one modification as disclosed in FIG. 3 may be utilized with good results. Referring now to FIG. 3, there is schematically illustrated a gas turbine engine 14 which is quite similar to the gas turbine engine 1 of FIG. 1, although without the compressor by-pass ducting 10. Engine 14 is equipped with a conduit type of exhaust 15 which exhausts the fuel-rich exhaust stream into a secondary engine 16. The secondary engine 16 may comprise a compressor 17, combustion chambers 18, and a further turbine wheel 19. The fuel-rich exhaust stream from engine 14 is introduced into the combustion chambers 18 of engine 16 where it is mixed with air from compressor 17 and, if necessary, additional fuel. The products of combustion pass through the turbine wheel 19 for rotation thereof. The power obtained from the shaft of engine 16 may be utilized for various purposes, or connected by means of gearing to the shaft of engine 14 for an increased power output. The modification as illustrated in FIG. 3 is exemplary of many arrangements of tandem or serial positioned power plants closely related to the well known topping process in steam turbine practice.

The invention thus described contemplates a high temperature gas turbine or the like jet apparatus wherein the maximum temperature will be limited only by the strength of refractory metals such as those of molybdenum, niobium, tantalum, and tungsten, and their alloys. In a gas turbine, the combustion gases in the high temperature turbine stages will be kept of controlled oxidation potential with respect to the metal used for the turbine buckets by burning fuel in excess of the stoichiometric ratio. As the temperature of these gases falls by extraction of energy in the form of useful work, additional air may be mixed and burned with the fuel-rich mixture, provided that a trioxidizing mixture does not result. Ultimately, an excess of air can be added to the gas mixture when the temperature is held below 1700° F., since structural materials of inherent oxidation resistance are known up to this value of temperature. It is to be further understood that the whole of the products of combustion need not be a reducing atmosphere, since it is contemplated that where general or limited parts are made of refractory metals the controlled atmosphere need be provided only adjacent these parts. For example, for the blades of a turbine wheel, fuel may be added upstream of the blades to burn and be a protective atmosphere while passing through the blades and thereafter to become oxidizing.

While other modifications of this invention and variations of apparatus which may be employed in the scope of the invention have not been described, the invention is intended to include all such as may be embraced within the following claims.

What I claim as new and desire to secure by Letters Patent of the United States is:

1. The method of increasing the operating temperature of a turbojet engine having critical operating parts including a metal from the group consisting of molybdenum and tungsten to the range of about 2000° F. to 3000° F., said method comprising combusting a fuel-air mixture in the engine which contains about 1.5 times the stoichiometric amount of fuel so that combustion products are produced which permit dioxides of molybdenum and tungsten to form and preclude formation of trioxides of these metals, and mixing additional air with the previously combusted fuel-air mixture after it has passed out of contact with the critical operating parts to effect further combustion thereof.
2. The method of operating a high temperature turbojet engine including compressor, combustion, turbine and exhaust sections, utilizing blades on the turbine wheel of said engine which include a metal selected from the group consisting of molybdenum and tungsten, combusting a fuel-air mixture in said engine which contains excess fuel sufficient to form combustion products preventing the formation of metal trioxides on the turbine buckets at

temperatures of 2000° to 3000° F., and mixing additional air with the previously combusted fuel-air mixture in the exhaust section of the engine to effect further combustion thereof at temperatures below 2000° F.

3. The method of operating a high temperature turbojet propulsion power plant including first and second turbine sections in which critical operating parts of at least one of said sections are constructed of a metal from the group consisting of molybdenum and tungsten, said method comprising combusting a fuel-air mixture rich in fuel in the power plant creating combustion products preventing the formation of trioxides of the metals molybdenum and tungsten at operating temperatures of from about 2000° F. to 3000° F., and mixing additional air with the combusted fuel-air mixture intermediate the first and second turbine sections to effect further combustion thereof

and to perform additional work in the second turbine section.
